UNITED STATES PATENT OFFICE

108,244

DESIGN FOR A CYLINDER REBORING-PLATE

Edward R. Michener, St. Louis, Mo., assignor to
H & H Machine & Motor Parts Company, St.
Louis, Mo., a corporation of Missouri

Application January 11, 1937, Serial No. 67,001

Term of patent 14 years

To all whom it may concern:

Be it known that I, Edward R. Michener, a citizen of the United States, residing at the city of St. Louis, State of Missouri, have invented a new, original, and ornamental Design for a Cylinder Reboring-Plate, of which the following is a specification, reference being made to the accompanying drawing forming a part thereof, in

which Figure 1 is a plan view, Figure 2 is an edge view, and Figure 3 is an inverted plan view of a cylinder reboring-plate embodying my design.

I claim—

The ornamental design for a cylinder reboring-plate, substantially as shown.

EDWARD R. MICHENNER.
